VALVE DEVICE

George K. Newell, near Pitcairn, Pa., assignor to
The Westinghouse Air Brake Company, Wil-
merding, Pa., a corporation of Pennsylvania

Application August 30, 1944, Serial No. 551,791

2 Claims. (Cl. 251—137)

1

This invention relates to a fluid pressure control device and more particularly to a valve device of the type for releasing fluid under pressure from a charged chamber or other volume.

The principal object of my invention is to provide a novel valve device of the above mentioned type for initiating the venting of fluid under pressure from a chamber or conductor and which is responsive to a force created by the flow of fluid from the conductor to reduce the fluid pressure in the chamber or conductor to a selected low value, the valve device functioning automatically to close off the flow of fluid from said chamber or conductor when the pressure of fluid therein has been reduced to said selected low value.

Other objects of my invention will appear in the following description.

In the accompanying drawing, Fig. 1 is a sectional view of a valve device constructed in accordance with the invention, and Fig. 2 is a lateral section taken on the line 2—2 of Fig. 1.

As shown in the drawing, this valve device comprises a body 1 having formed therein a chamber 2 connected to a fluid pressure conductor 3, and containing a valve 4 supported by a spring 5 which is carried by a cap nut 6 having screw threaded connection with the body 1. The valve 4 engages a seat member 4' and is for the purpose of controlling communication through a passage 7 provided in a wall 8 of the body, which wall separates the chamber 2 from a chamber 9 formed in the body by a cover 10 having screw threaded connection with the body.

The valve 4 is provided with a fluted stem 11 which projects through passage 7 into chamber 9, there being a plurality of flutes provided in the stem as shown in Fig. 2. Secured to the end of stem 11 within chamber 9 is a coaxially arranged disc 12, which may be circular in form and is spaced away from wall 8. One or more ports or openings 13 lead from chamber 9 to the atmosphere, said ports or openings being protected from entry of dirt, insects, etc. by a skirt 14 on the cover 10. This skirt is spaced from the body 1 and extends across the openings.

Disposed above the valve stem 11 and in axial alignment therewith is a plunger 15 which is slidably guided in a suitable opening in the cover 10. The inner end of said plunger projects into chamber 9 and is arranged for operative engagement with the adjacent end of valve stem 11. The other end of plunger 15 is provided with a hand button 16 for manual operation.

Interposed between and operatively engaging the button 16 and an exterior surface of the cover

10 is a spring 17 for normally urging the plunger 15 to the position in which it is shown on the drawing, that is, out of engagement with the valve stem 11. A disc 18 is secured to the inner end 5 of the plunger 15 for engagement with the cover 10 to prevent withdrawal of the plunger from the cover. With the plunger out of engagement with the valve stem 11 the spring 5 acting against the valve 4 maintains it seated, closing communication from the chamber 2 to chamber 9.

Operation

Let it be assumed that the conductor 3 is connected to a chamber or the like containing fluid under pressure and that it is desired to release the fluid under pressure from said chamber. To accomplish this, the plunger 15 will be depressed into engagement with the valve stem 11 and then actuated to force the valve 4 from its seat. With the valve 4 open, fluid under pressure will then flow from conductor 3 and the connected chamber or the like (not shown), and chamber 2, past said valve to chamber 9 and thence to the atmosphere. When the valve is being opened by the 20 operation of plunger 15, the disc 12 is moved in the direction of wall 8 and the fluid under pressure released past the valve then flows through the space between the disc and the wall to the atmosphere. This flow of fluid under pressure 25 will create a reduction in pressure on an area under the disc and adjacent the valve stem to a pressure below the opposing atmospheric pressure above the disc, thereby creating a force upon the disc which will act to hold the valve open against the opposing force of spring 5 and the pressure 30 of fluid in chamber 2 acting upon the valve. The plunger 15 may therefore be released and returned to its normal position upon the opening 35 of the valve 4.

The position which the disc 12 and the valve 4 will assume, with respect to the wall 8, as just described, will depend substantially upon the degree of reduction in pressure below atmosphere on the area under the disc above mentioned. 40 This reduction in pressure on the under side of disc 12 will in turn vary in proportion to the velocity of fluid under pressure flowing out of the end of the bore 7 into the space between the disc 12 and the wall 8. This velocity of fluid flow in 45 turn will depend upon and vary in proportion to the capacity of the valve and stem to release fluid under pressure from chamber 2 through the bore 7 as well as the pressure in the said chamber. This flow will also reduce as pressure of fluid in 50 the chamber 2 reduces and may also vary accord-

ing to the rate of supply of fluid under pressure to said chamber.

It will therefore be seen that the disc 12 will assume a position proportional to the pressure of fluid in chamber 2, while said pressure exceeds a certain degree. When the pressure in chamber 2 becomes reduced to this certain degree, an insufficient differential in pressure will be provided on the disc 12 to hold the valve open against the force of spring 5 and the pressure in chamber 2 10 acting upon the said valve, whereupon the valve will close.

The degree of force obtained for holding the valve open will also vary according to the area of disc 12 so that a relatively large disc will hold the valve 4 open until the pressure in chamber 2 is reduced to a lower degree than if the area of the disc were less. It will therefore be seen that the structure may be designed to automatically close and retain any desired pressure.

While this valve device has been described as being manually operated, it may also be used in other locations where its operation is automatically initiated. Such an installation, for example, might be in connection with roadside signal apparatus for the control of railway trains or the like, where a momentary force can be applied to the valve by an object along the right of way.

Having now described my invention, what I 30 claim as new and desire to secure by Letters Patent, is:

1. A valve device comprising a casing having a pressure chamber and a vent port connecting said chamber to a flat surface on said casing for releasing fluid under pressure from said chamber, a valve disposed in said chamber for closing said port, a spring for actuating said valve to close said vent port, means for opening said valve, a disc one side and the periphery of which is constantly subject to substantially atmospheric pressure and said disc being operative upon a sufficient reduction in pressure on its opposite side below atmospheric pressure on the one side to hold said valve open, means connecting said valve to said disc and

disposing said discs substantially coaxial with said vent port and with said opposite side parallel to said flat casing surface and so spaced from said surface as to provide between said surface and said opposite side of said disc a relatively restricted fluid flow communication from said vent port to the periphery of said disc whereby the pressure on said opposite side of said disc will be reduced below that on said one side to a degree proportional to the rate of venting of fluid through said vent port.

2. A vent valve device comprising a casing having a valve chamber adapted to receive fluid under pressure, and also having a smooth surface 15 of substantial area exposed to atmosphere and a passage-way connecting said valve chamber to said surface for releasing fluid under pressure from said chamber to atmosphere over said surface, a valve in said chamber for controlling flow 20 of fluid from said chamber through said passage, a stem for said valve extending through said passage with the end opposite said valve disposed beyond said surface, a member attached to the end of said stem opposite said valve and having 25 a surface spaced apart from, parallel to and adjacent said smooth surface, and means for actuating said stem to unseat said valve.
